UNITED STATES PATENT OFFICE.

QUIMBY S. BACKUS, OF WINCHENDON, MASSACHUSETTS.

RADIATOR.

SPECIFICATION forming part of Letters Patent No. 374,333, dated December 6, 1887.

Application filed June 29, 1887. Serial No. 242,837. (No model.)

To all whom it may concern:

Be it known that I, QUIMBY S. BACKUS, a citizen of the United States, residing at Winchendon, in the county of Worcester and State 5 of Massachusetts, have invented certain new and useful Improvements in Radiators; and I do hereby declare the following to be a full, clear, and exact description of the invention, such as will enable others skilled in the art to 10 which it appertains to make and use the same.

My invention relates to steam-radiators for warming apartments in dwelling-houses and like buildings; and it consists of a steam-radiator of peculiar construction, and its connection with other parts with which it is used. 15

In the accompanying drawings I have illustrated two forms of radiators embodying my invention, and have described the constructions shown, and set the invention forth fully 20 in the specification and claims.

Figure 1 is a transverse sectional view of my radiator used in connection with a steam-generator within the fire-niche. Fig. 2 is a 25 partial longitudinal section of the same construction. Fig. 3 is a transverse section. Fig. 4 is a front view. Fig. 5 is a plan view of a modified construction.

In my application No. 218,421, filed November 9, 1886, I have shown a mantel constructed 30 in such a manner as to act as a radiator. It is not unfrequently the case that a radiator is desired where a mantel is already in the house and is of such a character that it is desired to retain it. In such case I employ the radiator 35 forming the subject-matter of this application. In my former application the mantel constitutes the radiator. In my present construction my radiator is used with a mantel, and lies wholly within the same, and forms a fac- 40 ing for the space between the mantel and the fire-space.

In the said drawings, A designates the man- 45 tel, of usual form, surrounding a fire-place niche.

B is my radiator, which constitutes three sides 50 of a rectangle and occupies the space between the mantel and the grate or fire-space within the same, and which is now frequently filled by tiling or ornamental iron-work. This radiator is constructed of hollow shallow plates of thin material, and is provided with suitable inlet and outlet pipes for steam.

In Figs. 1 and 2 I have shown the fire-space or grate provided with a steam-generator, C, and a gas-log, D, for heating the same. The 55 steam-generator is connected with the upper part of the radiator by pipes c, and with the lower portion of the same by pipes d. (Best shown in Fig. 2.) The arrangement of these pipes is such that a circulation of the steam 60 through the radiator is secured, and the construction secures the radiation of the heat from the steam generated, as well as the direct action of the fire in heating the room.

The fire-place niche being cut off from the 65 chimney, I may provide my radiator with openings b on each side at the bottom, and openings b' at the top, to admit air to the space at the rear of the radiator to be heated and returned to the room. In case of the 70 apartment becoming too highly heated it can be ventilated by turning the damper E in the throat of the chimney.

The front walls of the radiator are prefer- 75 ably made with an outer surface of ornamental character in imitation of tiling or other pre-ferred form of ornamentation.

My improved radiator may also be used in connection with a distant steam-generator, it being supplied with the proper inlet and outlet pipes, as in other forms of radiators. These 80 are shown in dotted lines, Fig. 4, and in full lines in Fig. 5 at a a'.

Where my radiator is used in connection 85 with a distant generator, I may prefer to pro- vide additional heat-radiating surface by con- structing and connecting with said radiator a hollow fire-board fitting within and closing the grate or fire space. This radiator is shown at B' in Figs. 3, 4, and 5. In the drawings I 90 have shown this portion of my radiator set a little to the rear of that portion forming the jambs; but I may have the two portions in the same vertical plane. The two parts are con- 95 structed, in this instance, so that both are fur- nished with steam by the supply-pipe a, and discharge it through the outlet a'; but the sup- 100 ply-pipe may be connected to but one of the two parts, and the two parts of the radiator united by suitable connecting-pipes. In most instances I prefer to connect the two parts at one or more points, as shown in Figs. 4 and 5 at a'. In employing this form of my device the rear of the fire-niche is closed by a plate,

F, or other construction, and the radiator provided with the openings b and b' for permitting a circulation of air back of the radiator. Of course it will be understood that provision will be made in the usual way for permitting the air within the radiator to escape and for drawing off any water of condensation that may form within. The front of the part B' may be provided with any preferred form of ornamentation, and this part is preferably made detachable from the other, so that it can be taken out and a gas or other fire substituted when desired.

What I claim, and desire to secure by Letters Patent, is—

1. A radiator consisting of a shallow hollow plate located within a mantel, and forming a facing for the space between the mantel and the fire-space, and inlets and outlets for said plate, substantially as described.
2. A radiator consisting of a shallow hollow plate forming three sides of a rectangle, located within a mantel, and forming a facing for the space between the mantel and the fire-

space, and a hollow plate filling the space 25 within the radiator, and connected thereto, and inlets and outlets, substantially as described.

3. The combination, with a fire-niche, of a mantel, and a radiator consisting of shallow 30 hollow plates at the sides and top of the fire-niche, and between the same and the mantel, and inlets and outlets, substantially as described.

4. The combination, with a fire-niche or 35 fire-space and a mantel, of hollow shallow plates at three sides of the fire niche or space between the same and the mantel, of a steam-generator within the fire-niche, and connections between the steam-generator and the radiator forming a steam-circuit, substantially as described.

In testimony whereof I affix my signature in presence of two witnesses.

QUIMBY S. BACKUS.
